UNITED STATES PATENT OFFICE.

THOMAS W. NEEL AND ALBERT G. SHAFFER, OF VENTURA, CALIFORNIA.

COMBINED STOCK EXTENSION AND HOLSTER FOR FIREARMS.

Application filed December 29, 1924. Serial No. 758,579.

To all whom it may concern:

Be it known that we, THOMAS W. NEEL and ALBERT G. SHAFFER, citizens of the United States, residing at Ventura, in the county of Ventura and State of California, have invented a new and useful Combined Stock Extension and Holster for Firearms, of which the following is a specification.

This invention relates to a holster of that type to which a firearm can be attached so that the holster can be used as a stock extension for the firearm, to insure accuracy in firing.

An important object of the invention is to facilitate rapid assembling of the holster and firearm.

Another object is to insure against slipping of the firearm in the clamping means of the holster.

20 A further object is lightness, combined with longitudinal stiffness of the holster.

The accompanying drawings illustrate the invention.

Fig. 1 is a side elevation of a combined stock-extension and holster constructed in accordance with the provisions of this invention, a firearm being indicated as supported by the holster in firing position.

30 Fig. 2 is an enlarged inverted plan view of the holster shown in Fig. 1.

Fig. 3 is an enlarged fragmental section on the line indicated by line 3—3, Fig. 1.

Fig. 4 is an enlarged front end view of the clip with the stock of the firearm in place therein.

The holster is indicated in general by the character *a* and the firearm by the character *b*, in Fig. 1. The holster comprises outer sheet members 4 of leather, or the equivalent of such material, and an intermediate stiffening member 5 of sheet metal. The member 5 may be constructed, for example, of thin sheet metal. The members 4 and 5 are wider at one end than the other and are concave at one end, as indicated at 6, so as to fit the shoulder. The members 4, 5, 6 constitute a stock-extension portion.

Secured to one of the members 4 is a member 7 of leather, or the like, which, in conjunction with said member 4, forms a pocket to receive the barrel portion of the firearm *b*, in a manner well understood in this art. The smaller ends of the members 4, 5 extend beyond the member 6, as indicated at 8, and secured to the portion 8 by rivets 9, or their equivalent, is a clip comprising a

spring metal member 10 having a covering 11 of leather or its equivalent. The member 10 has flat side portions and curved end portions to accurately fit the pistol stock *c*. 60

The member 10 is split at one end, as indicated at 12, and the opposite end of said member is provided with an integral cross member 13 that constitutes a shoulder which the heel of the pistol stock *c* engages when 65 the stock is positioned in the member 10, as in Fig. 1. The provision of the shoulder 13 is important as it materially assists in connecting the firearm firmly in the holster. The cross member 13 is notched at its forward edge at 14, and in the notch fits the release catch of the cartridge magazine of the pistol *b*. This catch is indicated at *d* in Fig. 1.

From the foregoing description it will be 75 seen that the firearm can be inserted in the holster for convenient carrying of the firearm, in a manner well understood in this art. The firearm may be drawn and used in the hand without attaching it to the holster 80 but, when greater accuracy of firing is desired, the forward portion of the lower end of the stock *c* will be thrust forwardly and downwardly into the clip 10 and the stock will then be swung downwardly and rearwardly to bring the heel thereof into engagement with the cross member 13, with the catch *d* inserted in the notch 14. The forward end portions of the members 10, 11 have notches 15 (see Fig. 4), so that the forwardly and downwardly projecting toe *e* of the stock *c* will engage the notches 15 and thus, in conjunction with the cross member 13, prevent the pistol from tilting upwardly and rearwardly in relation to the holster. 85 90 95

To remove the pistol from the slip 10, it is only necessary to forcibly tilt the pistol forwardly and downwardly relative to the holster so as to swing the heel of the stock *c* upwardly away from the cross member 13, 100 the operation being just the reverse of that employed in mounting the pistol in the clip.

The improved holster is exceedingly simple in construction and, it will be seen from the foregoing description of the operations of mounting and dismounting the pistol, that said operations are very simple and can be quickly performed.

We claim:

1. A combined stock-extension and holster 110 for a firearm comprising, outer sheet members, a sheet metal stiffening member be-

- between the outer members, a member secured to one of the outer members and forming in conjunction therewith a pocket to receive the barrel portion of a firearm, and a split spring clip secured to one of the outer members and having an integral cross member to engage the heel of the stock of the firearm.
2. A combined stock-extension and holster for a firearm comprising a stock-extension portion, a member forming in conjunction with said portion a pocket to receive the barrel portion of a firearm, and a split spring clip secured to the stock-extension portion and having an integral cross member to engage the heel of the stock of the firearm.
3. A combined stock-extension and holster for a firearm comprising, a stock-extension

portion, a member forming in conjunction with said portion a pocket to receive the barrel portion of a firearm, and a split spring clip secured to the stock-extension portion and having an integral cross member to engage the heel of the stock of the firearm, the opposite sides of the clip adjacent to the split being notched to receive the forwardly and downwardly projecting toe of the stock to prevent in conjunction with the cross member tilting of the firearm upwardly and rearwardly.

Signed at Los Angeles, California, this 30
22nd day of December 1924.

THOMAS W. NEEL.
ALBERT G. SHAFFER.
